[57] ABSTRACT

A control system controls the acid strength of reaction acid in an alkylation unit reacting an olefin with an isoparaffin in the presence of the reaction acid to eventually produce an alkylate. The system senses the actual reaction acid strength, the discharge acid flow rate, the flow rate of discharge acid leaving the alkylation unit, the bottom products flow rate and the alkylate content of the bottoms product from a debutanizer tower and the propylene and butylene content of the olefin stream entering the alkylation unit. Using equations hereinafter disclosed, along with economic values associated with the acid and the alkylate, the control system periodically determines the optimum reaction acid strength. When the change in the reaction acid strength necessary to achieve the optimum reaction acid strength is less than a predetermined change, the necessary change is implemented. When the necessary change is greater than the predetermined change, the reaction acid strength is changed by an increment equal to the predetermined change. Where the reaction acid strength is decreased to achieve an optimum reaction acid strength, a minimum limit is imposed on the reaction acid strength to prevent undesirable side reactions, such as olefin polymerization, from occurring.

MEANS AND METHOD FOR ACHIEVING AN
OPTIMUM ACID STRENGTH FOR AN
ALKYLATION UNIT

BACKGROUND OF THE INVENTION

1. Field of the Invention

The present invention relates to control systems and methods in general and, more particularly, to a control system and method for an alkylation unit.

2. Description of the Prior Art

Heretofore, control systems for alkylation units such as disclosed in U.S. applications Ser. Nos. 169,385 and 169,443, assigned to Texaco Inc., assignee of the present invention, control the reaction acid strength as a function of the deterioration or the anticipated deterioration of the reaction acid during the alkylation process. The reaction acid strength is maintained at a predetermined value.

The system and method of the present invention is completely different in concept from the aforementioned control systems. The present system and method controls the acid strength as a function of the economic values of the acid and the alkylate so that an optimum acid strength may be achieved. Furthermore, the present system and method may be used in conjunction with the control systems disclosed in the aforementioned applications to maintain the reaction acid strength at an optimum value.

SUMMARY OF THE INVENTION

A system controls the strength of reaction acid in a reaction unit wherein an isoparaffin is reacted with an olefin in the presence of the reaction acid to provide an acid-hydrocarbon mixture to a settler where a hydrocarbon product is separated from the reaction acid and provided to a de-butanizer tower whose bottom products include alkylate; and a portion of the reaction acid is recycled while the remaining reaction acid is discharged from the alkylation unit; and wherein fresh acid is added to the recycle acid to affect the strength of the reaction acid. The circuit includes control apparatus which controls the reaction acid in accordance with a control signal. The flow rates of the reaction acid and the bottom products are sensed and corresponding signals provided. Signals corresponding to concentrations of different constituents of the olefin and of the alkylate in the bottom products stream are also provided. Apparatus senses the strength of the reaction acid and provides a signal representative of the acid strength. Signals corresponding to the economic values of acid and of octane of the alkylate are provided. The circuit provides the control signal in accordance with the signals corresponding to one of the acid flow rates, the alkylate flow rate, the concentration of the constituents of the olefin and of the alkylate, the acid strength of the reaction acid and the economic values of the acid and the octane rating to achieve an optimum acid strength for the reaction acid.

The objects and advantages of the invention will appear more fully hereinafter from a consideration of the detailed description which follows, taken together with the accompanying drawings wherein one embodiment of the invention is illustrated by way of example. It is to be expressly understood, however, that the drawings are for illustration purposes only and are not to be construed as defining the limits of the invention.

DESCRIPTION OF THE DRAWINGS

FIG. 1 shows a simplified block diagram of a system for controlling the strength of reaction acid in an alkylation unit which is also shown in partial schematic form.

FIG. 2, comprising FIGS. 2A-2G, is a diagrammatic representation of pulses occurring during the operation of the system shown in FIG. 1.

FIGS. 3 and 4 are detailed block diagrams of the programmer and the acid strength signal means, respectively, shown in FIG. 1.

FIG. 5 is a detailed block diagram of the olefin signal means shown in FIG. 1.

FIG. 6 is a detailed block diagram of the optimum control system shown in FIG. 1, constructed in accordance with the present invention.

FIGS. 7 through 10 are detailed block diagrams of the θ computer, the ϕ computer, the p computer, and the R and S computer shown in FIG. 6. FIGS. 11A and 11B, when matched along matching line A-A, is a detailed block diagram of the control means in FIG. 6.

DESCRIPTION OF THE INVENTION

Referring to FIG. 1, there is shown a portion of an alkylation unit in which an olefin is reacted with isoparaffin in the presence of a catalyst, such as sulfuric or hydrofluoric acid and which is hereinafter referred to as the reaction acid, to form a higher molecular weight isoparaffin. For purpose of explanation, the acid in the following description shall be sulfuric acid. The olefin may be butylenes, propylene or a mixture of butylenes and propylene, while the isoparaffin may be isobutane. The control system shown in FIG. 1 controls the strength of the reaction acid during the reaction by determining the actual reaction acid strength to achieve an optimum strength.

The olefin and isoparaffin enter a contactor 4, by way of a line 6, where the olefin and isoparaffin are contacted with the reaction acid entering by way of a line 7. Contactor 4 provides an acid-hydrocarbon mix by way of a line 8 to an acid settler 12. Settler 12 separates the hydrocarbon product from the reaction acid and the hydrocarbon product is provided to a debutanizer tower 13 through a line 14 while the reaction acid is removed by way of a line 16. Acid settler 12 may be the only acid settler in the unit or it may be the last acid settler of a group of acid settlers. A top products stream leaves tower 13 by way of a line 11 while a bottom products stream, which includes alkylate, leaves tower 13 by way of a line 15. Fresh acid enters line 16 by way of a line 17 as needed to maintain a desired reaction acid strength. A pump 20 pumps the reaction acid from line 16 into line 7. A portion of the reaction acid in line 7 is discharged by way of a line 21. The discharge acid may be provided to another alkylation unit or disposed of.

An acid strength analyzer 22 periodically samples the acid in line 16 and provides signals E_1 through E_4 . Acid strength analyzer 22 may be of the type fully disclosed in U.S. application Ser. No. 881,359 filed on Dec. 2, 1969 by R. A. Culp et al. and assigned to Texaco Inc., assignee of the present invention. The acid sample is analyzed by titrating the sample with caustic from a source 24 entering analyzer 22 by way of a line 25 at a constant rate. The start of each sampling cycle

of the acid in line 16 is controlled by a signal E_5 from a programmer 27, as hereinafter described. Signal E_1 , shown in FIG. 2A, from analyzer 22 occurs at the time at which titration is initiated, while signal E_2 , shown in FIG. 2B, occurs at the time at which titration is completed. The occurrence of pulse signal E_3 indicates that the amplitude of signal E_4 corresponds to the density of the acid sample. Signals E_1 , E_2 from analyzer 22 are applied to programmer 27, while signals E_3 , E_4 are applied to acid strength signal means 35, which is hereinafter described in detail.

Programmer 27 controls the development of a signal E_{16} corresponding to an optimum flow rate of discharge acid. The quantity of fresh acid entering the alkylation unit is controlled by controlling the quantity of acid being discharged to control the strength of the reaction acid. Programmer 27, which is described in detail hereinafter, receives a pulse signal E_9 from chromatograph means 36. Chromatograph means 36 samples the stream in line 6 and provides signals E_9 and E_{10} . The peaks of signal E_{10} correspond to concentrations of different constituents of the stream in line 6. Each pulse in pulse signal E_9 coincides with a different peak of signal E_{10} . Programmer 27 provides a signal E_5 , corresponding to the titration time of the reaction acid sample with a caustic, a reset pulse E_7 and control pulses E_A , E_B through E_N . Signal E_5 and control pulses E_A , E_B are applied to acid strength signal means 35 which also receive direct current voltages V_1 through V_4 from a source of direct current voltages 38.

Acid strength signal means 35, which is described in detail hereinafter, provides a signal E_{11} , corresponding to the strength of the reaction acid, to an optimum control system 40. For convenience, the term acid strength shall hereinafter be used in lieu of reaction acid strength whether said strength is an actual strength, a predicted strength or a reference strength. Control system 40, which is described in detail hereinafter, determines the optimum acid strength and provides a signal E_{16} corresponding to a target flow rate for the discharge acid to achieve an optimum acid strength. Control system 40 receives direct current voltages V_6 through V_{24} and V_{30} from source 38 and a signal E_{12} from olefin signal means 41 corresponding to the ratio M of propylene in line 6 to the olefins in line 6. Control system 40 also receives a signal E_{14} from a sensor 42 in line 21 representative of the flow rate of the discharge acid which is substantially equal to the flow rate of the fresh acid in line 17, and a signal E_{15} , corresponding to the bottom products flow rate, from a sensor 42A in line 15.

Olefin signal means 41 provides signal E_{12} in accordance with signal E_{10} from chromatograph means 36 and control pulses E_D through E_G and E_N from programmer 27.

Chromatograph means 43 samples the bottom products stream in line 15 to provide a pulse signal E_{9A} to programmer 27 and a signal E_{10A} to alkylate signal means 44 receiving direct current voltages V_5 through V_{51} from direct current voltage source 38 and pulses E_O , E_P , E_Q , E_R , E_S , E_T , E_U , E_V , E_W , E_X , E_Y , E_Z from programmer 27. The peaks of signal E_{10A} correspond to concentrations of different constituents of the bottom products. Each pulse in pulse signal E_{9A} coincides with a different peak of signal E_{10A} . Alkylate signal means 44

is controlled by pulse signals E_0 through E_2 from programmer 27 to provide a signal E_{17} to optimum control system 40 corresponding to the concentration of alkylate in the bottom products stream in line 15.

Alkylate signal means 44 is similar to the olefin signal means described in the aforementioned U.S. application Ser. No. 169,443 except that signal E_{17} corresponds to the normalized constituent with six or more carbon atoms. Olefin signal means 41 is also similar to alkylate signal means 44, except that alkylate signal means 44 must sample and hold the peaks of signal E_{10A} corresponding to the concentrations of ethane, propane, isobutane, normal butane, isopentane, normal pentane, propylene, butylene, pentylene, and all compounds with six or more carbon atoms. Alkylate signal means 44 normalizes the determined concentration of compounds with six or more carbon atoms by summing all of the sample and held peaks of signal E_{10A} and dividing the held peak of signal E_{10A} corresponding to the concentration of compounds with six or more carbon atoms to provide signal E_{17} .

Signal E_{16} is applied to a conventional type flow recorder controller 50 receiving signal E_{14} from flow rate sensor 42 and providing a signal to a valve 52 in line 21 to control the flow rate of the discharge acid.

The flow rate of the fresh acid in line 17 is controlled as a function of the discharge acid flow rate to affect the acid strength. When the discharge acid flow rate is increased, the acid level in acid settler 12 decreases. A level sensor 56 senses the acid level in settler 12 and provides a corresponding signal to a conventional type level recorder controller 57. Controller 57, whose preset set point corresponds to a predetermined acid level for settler 12, provides a signal, corresponding to the difference between the set point acid level and the settler 12 acid level, to a valve 60 in line 17 to increase the fresh acid flow rate thereby restoring the acid level in acid settler 12 to the predetermined level and increasing the acid strength. When the discharge acid flow rate is decreased, the acid level in settler 12 increases causing a decrease in the fresh acid flow rate and a decrease in acid strength.

Reset pulse E_7 developed in programmer 27 resets circuits in acid strength analyzer 22, programmer 27, chromatograph means 36, optimum control system 40 and chromatograph means 43.

Referring to FIG. 3, programmer 27 includes a conventional type "on-off" switch 101 which receives a direct current voltage V_O from source 38. Switch 101 controls the operation of control system 40. When activated, switch 101 passes voltage V_O to operate clock means 105. Clock means 105 periodically provides a reset pulse E_7 . The pulse repetition rate of pulses E_7 should be of sufficient duration to allow the alkylation unit to stabilize.

Pulse signal E_9 from chromatograph means 36 is applied to an AND gate 106 which controls the development of pulse signals E_D through E_G . AND gate 106 is enabled by a high level direct current output from a logic decoder 108. When enabled, pulse signal E_9 passes through AND gate 106 into a conventional counter 110 which counts the pulses in signal E_9 coinciding with different peaks in signal E_{10A} . Logic decoder 108 decodes the count in counter 110 to provide a plurality of outputs to monostable multivibrator 114.

Logic decoder 108 may be of the type that includes AND gates connected to each stage of counter 110 in a manner so that each AND gate provides an output for predetermined counts in counter 110. Upon reaching a count of 10, the direct current output provided by logic decoder 108 to AND gate 106 goes to a low level thereby disabling AND gate 106 to block pulse signal E_9 to prevent further counting by counter 110.

Monostable multivibrators 114 represent a plurality of monostable multivibrator, each monostable multivibrator is connected to a different AND gate in decoder 108 and is triggered by its output to provide a pulse. Monostable multivibrators 114 provide a plurality of control pulses E_D through E_G which coincide with certain peaks of signal E_9 corresponding to the various olefin constituents of the stream in line 6 as determined by chromatograph means 36. FIG. 2C shows pulse E_D while FIG. 2D shows pulse E_G . It should be noted that there is only one break associated with pulse E_G . This is because pulse E_D preceded pulse E_G in time and in this particular example, pulse E_G is used to start the timing sequence and is therefore time related to the pulses shown in FIGS. 2F and 2G.

Pulse E_G from monostable multivibrators 114 triggers yet another monostable multivibrator 116 which acts as a time delay and provides a pulse to a flip-flop 117. The trailing edge of the pulse E_G from multivibrator 116 triggers flip-flop 117 to its set state. The output of a flip-flop is a high level direct current voltage, when the flip-flop is in a set state and a low level direct current voltage when the flip-flop is in a clear state. Flip-flop 117 provides its output as signal E_A , shown in FIG. 2E, to acid strength signal means 35 and to an AND gate 118 partially enabling AND gate 118.

The end of titration signal E_2 triggers a flip-flop 132 to a set state causing flip-flop 132 to provide a high level direct current output to AND gate 118. AND gate 118 controls the development of pulse signals E_B and E_N so that they only occur after the acid strength analysis and the olefin and isoparaffin stream analysis have been completed. When fully enabled, AND gate 118 passes timing pulses from a clock 120 to a conventional counter 124. A logic decoder 125 decodes the count in counter 124 to provide two trigger outputs, at different times, to two monostable multivibrators shown, as monostable multivibrators 127. Monostable multivibrators 127 provides signals E_N and E_B as shown in FIGS. 2F and 2G, respectively.

The titration time signal E_5 is developed by a flip-flop 140, a clock 141, AND gate 142, monostable multivibrators 144 and 145, a counter 148, a storage register 150 and a digital-to-analog converter 151. The start of titration signal E_1 from acid strength analyzer 22 triggers flip-flop 140 to a set state. The high level output from flip-flop 140 enables AND gate 142 causing it to pass timing pulses to counter 148. Counter 148 counts the timing pulses passed by AND gate 142. The end of titration signal E_2 triggers flip-flop 140 to a clear state. The resulting low level output from flip-flop 140 disables AND gate 142. When disabled, AND gate 142 blocks the timing pulses from clock 141 so that the count in counter 148 corresponds to the time interval between signals E_1 , E_2 which is the titration time.

The change in the output from flip-flop 140 from a high level to a low level triggers multivibrator 144 caus-

ing it to provide a time delay pulse. The trailing edge of the pulse from multivibrator 144 triggers multivibrator 145 so that multivibrator 145 provides a pulse after counter 148 has completed a count. The pulse from multivibrator 145 controls storage register 150 to accept and store the count from counter 148. Digital-to-analog converter 151 converts the count stored in register 150 to signal E_5 .

AND gates 106A, receiving signal E_{9A} and 118A; counters 110A and 124A; logic decoders 108A and 125A; and monostable multivibrators 114A and 127A cooperate in a manner similar to the cooperation of AND gate 106, counter 110, logic decoder 108 & monostable multivibrators 114 to provide pulses E_0 through E_z . Pulses E_0 through E_x coincide with different peaks of signal E_{10A} which corresponds to the concentration of alkylate in the bottom products. Pulses E_y , E_z are sampling pulses which control sample and hold circuits.

Reset pulse E_7 resets counters 110, 110A, 124, 124A and 148, flip-flops 117, 117A and 132 and storage register 150.

Referring to FIG. 4, acid strength signal means 35 provides signal E_{11} corresponding to the acid strength A_1 in accordance with the following equations:

$$1. A_1 = [(VOL_C) (N_c) (MEQ_A) / W_A]$$

where VOL_C is the volume of caustic required by the titration of the acid sample, N_c is the normality of the caustic, MEQ_A is milliequivalent weight of the acid, and W_A is the weight of the acid. Equation 1 may be rewritten as:

$$2. A_1 = [(\Delta T) (FR_c) (N_c) (MEQ_A) / (D_A) (VOL_s)]$$

where ΔT is the titration time, FR_c is the flow rate of the caustic, D_A is the density of the acid and VOL_s is the volume of the acid sample.

Acid strength signal means 35 includes sample and hold circuits 160, 161, multipliers 162 through 162C, a divider 163 and an electronic switch 164. Signal E_3 from analyzer 22, which occurs when signal E_4 corresponds to the density D_A of the acid sample, controls sample and hold circuit 160 to sample and hold signal E_4 . The output of sample and hold circuit 160 is applied to multiplier 162 where it is multiplied with direct current voltage V_1 which corresponds to the volume VOL_s of the acid sample. Multiplier 162 provides a signal corresponding to the denominator in equation 2.

Multiplier 162A multiplies the titration time signal E_5 from programmer 27 with voltage V_4 from source 38, which corresponds to the caustic flow rate to provide a product signal corresponding to $(\Delta T) (FR_c)$.

55 The product signal from multiplier 162A is multiplied with voltage V_2 , corresponding to the normality of the caustic, which by way of example, may be 0.2 meq/ml, by multiplier 162B to provide a product signal to multiplier 162C where it is multiplied with direct current voltage V_3 . Voltage V_3 corresponds to the milliequivalent weight MEQ_A of the acid which for purpose of illustration may be sulphuric acid H_2SO_4 whose milliequivalent weight is 0.04904 gram/meq.

60 The product signal from multiplier 162C corresponds to the numerator in equation 2. Divider 163 divides the numerator signal from multiplier 162C with the denominator signal from multiplier 162 to provide

a signal, which corresponds to the sensed acid strength A_1 , to electronic switch 164. Electronic switch 164 is controlled by pulse signal E_A so as to pass the acid strength signal from divider 163. Sample and hold circuit 161 is controlled by pulse E_B from programmer 27 to hold the A_1 signal passed by switch 164 to provide signal E_{11} corresponding to the acid strength A_1 .

Olefin signal means 41 provides a ratio M signal E_{12} , which is used to determine an octane adder factor as hereinafter explained, in accordance with the following equation:

$$3. M = (\text{propylene}/\text{olefins}) \times 100\%$$

Referring to FIG. 5, the peaks of signal E_{10} from chromatograph means 36 correspond to the concentrations of different constituents of the charge olefin and isoparaffin in line 6. Sample and hold circuits 170 through 170C are controlled by pulse signals E_D through E_G to hold some of the different peaks of signal E_{10} . The following table relates a particular sample and hold circuit to a corresponding olefin constituent of the stream in line 6.

CIRCUIT	CONSTITUENT
170	Propylene
170A	Butylenes
170B	Pentylenes
170C	All olefinic compounds with six or more carbon atoms

The outputs from sample and hold circuits 170 through 170C are applied to multipliers 171 through 171C where they are multiplied with voltages V_5 through V_{sc} , corresponding to scaling factors pertaining to the particular constituents. By way of example, the voltages V_5 through V_{sc} may correspond to 0.2, 0.10, 0.02 and 0.10, respectively. The product signals from multipliers 171 through 171C are sampled and held by circuits 172 through 172C, respectively, in response to pulse signal E_N from programmer 27. Sample and hold circuits 172 through 172C are used so that outputs corresponding to the various olefin concentrations of the charge olefin and isoparaffin in line 6 may be presented simultaneously to summing means 175. Summing means 175 provides a signal corresponding to the denominator of equation 3.

A divider divides the output from sample and hold circuit 172, which corresponds to the numerator of equation 3, with the sum signal from summing means 175 to provide the ratio M signal E_{12} .

It has been determined from empirical data that there exists an economic relationship between the octane rating of the alkylate provided by an alkylation unit and the strength of the reaction acid in the alkylation unit. Further, if the alkylate production rate is maintained at a constant value then the profit of the alkylation unit will vary as a function of the acid strength. An equation may be formulated to describe the alkylation unit's profit. The profit equation may be a second order equation such as Equation 4 or a linear equation such as Equation 5.

$$4. p = Q + RA + SA^2$$

$$5. p = Q + RA$$

where p is the differential profit, Q , R and S are constants and A is acid strength.

For the situation where Equation 4 describes the alkylation unit's profit, a first and second derivative of Equation 4 may be taken to yield equations 6 and 7.

$$6. dp/dA = R + 2SA$$

$$7. d^2p/dA^2 = 2S$$

$$8. A = -R/2S$$

When S is not 0, the maximum or minimum point of a curve described by Equation 4 can be determined by setting Equation 6 equal to 0 and solving for A as shown in Equation 8. When S is negative, the point is a maximum point and Equation 4 is used to control the alkylation unit. When S is positive the point is a minimum point. When S is positive or substantially equal to zero, equation 5 is used to control the alkylation unit. The values for S and R can be determined by increasing the acid strength by a predetermined amount to a value A_2 and decreasing the acid strength by a predetermined amount to a value A_3 and rewriting Equation 4 for the three acid strength conditions.

$$9. A_2 = A_1 + \Delta, \text{ and}$$

$$10. A_3 = A_1 - \Delta$$

where Δ is the predetermined acid strength change and by way of example may be 0.1 weight percent.

$$11. p_1 = Q + RA_1 + SA_1^2$$

$$12. p_2 = Q + RA_2 + SA_2^2$$

$$13. p_3 = Q + RA_3 + SA_3^2$$

The profit differentials p_1 , p_2 and p_3 may be determined by subtracting the present profit position P_1 from the profit positions P_1 , P_2 and P_3 . The profit position equations for P_1 , P_2 and P_3 are as follows:

$$14. P_1 = (\phi_1)(ALR)(V_o) - (AR_1)(V_A) - k$$

$$15. P_2 = (\phi_2)(ALR)(V_o) - (AR_2)(V_A) - k$$

$$16. P_3 = (\phi_3)(ALR)(V_o) - (AR_3)(V_A) - k$$

where AR_1 , AR_2 and AR_3 are acid rates for acid strength A_1 , A_2 and A_3 , respectively, in tons per day, V_A and V_o are predetermined economic values for the acid and octane rating of the alkylate, ALR is the alkylate production rate in barrels per day, ϕ_1 , ϕ_2 and ϕ_3 are octane adder factors for acid strengths A_1 , A_2 and A_3 , respectively and k represents constant production costs. Thus, p_1 is zero, while p_2 and p_3 are described by equations 17 and 18.

$$17. p_2 = (AR_1 - AR_2)(V_A) + (\phi_2 - \phi_1)(ALR)(V_o)$$

$$18. p_3 = (AR_1 - AR_3)(V_A) + (\phi_3 - \phi_1)(ALR)(V_o)$$

The octane adder ϕ may be written in general form as

$$19. \phi = K_a(A - A_{90}) + K_b(A - A_{90})^2 K_c(A - A_{90})^3 + K_d(A - A_{90})^4 + K_e(A - A_{90})^5$$

where K_a through K_e are factors associated with a particular alkylation unit for a particular acid strength and a particular M ratio, which may have the following values:

Factor	$M \leq M_L$	$M \geq M_U$
K_a	0.5115	0.0
K_b	-0.05582	0.0
K_c	0.0	-0.003609
K_d	0.0	0.0
K_e	0.00001363	0.0

where M_L is 35 percent and M_U is 60 percent.

From the factor table we may write the following equations for ϕ_L , which is used when M is equal to or less than 35 percent, ϕ_U for use when M is equal to or greater than 60 percent and ϕ_{L-U} for use when M is greater than 35 percent but less than 60 percent.

$$20. \phi_L = 0.5115(A - A_{90}) - 0.05582(A - A_{90})^2 + 0.00001363(A - A_{90})^5$$

$$21. \phi_u = -0.003609(A - A_{90})^3$$

$$22. \phi_{L-U} = \phi_L \left(\frac{M_U - M}{M_U - M_L} \right) - \phi_u \left(\frac{M - M_L}{M_U - M_L} \right)$$

The acid rate AR_1 and the alkylate rate ALR are obtained by converting the flow rates of the reaction acid and the alkylate in the bottom products, respectively, from barrels per hour to tons per day and to barrels per day, respectively, in accordance with equations 23 and 24.

$$23. AR_1 = (H)(FR_A)$$

$$24. ALR = (FR_{BP})(J)(ALK)$$

where FR_A and FR_{BP} are the flow rates of the reaction acid and the bottom products, respectively, H and J are conversion factors which by way of example may have values of 7.7112 hr-ton/day-bbl and 24 hrs/day, respectively, and ALK is the concentration of alkylate in line 15. Acid rates AR_2 and AR_3 for increased and decreased, respectively, acid strength conditions can be determined from equations

$$25. AR_2 = (\theta_2/\theta_1) AR_1$$

$$26. AR_3 = (\theta_3/\theta_1) AR_1$$

The general equation for an acid multiplier is

$$27. \theta = K_f + K_g(A - A_{90}) + K_h(A - A_{90})^2 + K_i(A - A_{90})^3 + K_j(A - A_{90})^4 \Theta_k(A - A_{90})^5$$

where K are factors associated with a particular alkylation unit and acid strength condition. By way of example for an acid strength equal to or greater than 90 weight percent: $K_f = 1.0$, $K_g = 0.03686$ and $K_h = 0.02454$ while K_i , K_j and K_k are equal to 0.0. Therefore equation 27 may be rewritten as:

$$28. \theta = 1.0 + 0.03686(A - A_{90}) + 0.02454(A - A_{90})^2$$

The multipliers θ_1 , θ_2 and θ_3 are determined from equation 28 by substituting A_1 , A_2 and A_3 , respectively, for A .

Equations 29 through 31 are as follows:

$$29. R = [p_1(A_2^2 - A_3^2) + p_2(A_3^2 - A_1^2) + p_3(A_1^2 - A_2^2)]/D$$

$$30. S = [p_1(A_3 - A_2) + p_2(A_1 - A_3) + p_3(A_2 - A_1)]/D$$

$$31. D = A_1(A_2^2 - A_3^2) + A_2(A_3^2 - A_1^2) + A_3(A_1^2 - A_2^2)$$

However, since p_1 is zero, equations 29 and 30 may be rewritten as

$$32. R = [p_2(A_3^2 - A_1^2) + p_3(A_1^2 - A_2^2)]/D \text{ and}$$

$$33. S = [p_2(A_1 - A_3) + p_3(A_2 - A_1)]/D, \text{ respectively.}$$

The values for R and S may be inserted in equation 8 to determine the optimum acid strength A_o .

When controlling the acid strength to achieve an optimum value, it is highly desirable that the change in the acid strength should not exceed the predetermined amount Δ . When required change to achieve the optimum acid strength is greater than Δ , the acid strength is changed by the amount Δ .

In controlling the acid strength to achieve an optimum strength the acid strength should not be allowed to drop below 90 weight percent so as to prevent undesirable side reactions, such as olefin polymerization from occurring.

When it has been determined that S is positive or zero, equation 5 is used to control the acid strength. Since equation 5 is a linear equation, differential profit points p_1 , p_2 and p_3 lie along a straight line. However, it is not known which point, p_2 or p_3 , offers the greater profit. Differential profit points p_2 and p_3 are compared with each other. When p_2 is greater than p_3 , the reaction acid strength is increased by the amount Δ . When p_3 is greater than p_2 , the reaction acid strength is decreased by the amount Δ .

Referring now to FIG. 6, optimum control system 40 includes a θ computer 200 which receives signal E_{11} corresponding to the sensed acid strength, and direct current voltages V_6 through V_9 . Computer 200 provides a signal E_{50} corresponding to the term θ_1 in accordance with equation 28. Voltage V_6 corresponds to A_{90} , while voltages V_7 - V_9 correspond to the factors 1.0, 0.03686 and 0.02454 in equation 28, respectively. Referring also to FIG. 7, subtracting means 201 in computer 200 subtracts voltage V_6 from signal E_{11} to provide an output corresponding to the term $(A_1 - A_{90})$. A multipliers 202 effectively squares the output from subtracting means 201 while another multiplier 203 multiplies the output from subtracting means 201 with voltage V_8 . The output from multiplier 202 is multiplied with voltage V_9 by a multiplier 207. Summing means 208 sums voltage V_7 with the outputs from multipliers 203, 207 to provide signal E_{50} .

20 Direct current voltage V_{10} corresponds to the predetermined change Δ for the acid strength. Summing means 212 in FIG. 6 sums signal E_{11} with voltage V_{10} to provide a signal E_{11A} corresponding to the increased acid strength A_2 . Similarly subtracting means 213 subtracts voltage V_{10} from signal E_{11} to provide a signal E_{11B} corresponding to the reduced acid strength A_3 . Signals E_{11A} , E_{11B} are applied to θ computers 200A and 200B, respectively. Elements having a number with a suffix are connected and operate in a similar manner to elements having the same number without a suffix. Computers 200A, 200B also received direct current voltages V_6 through V_9 to provide θ_2 signal E_{50A} and θ_3 signal E_{50B} , respectively. A pair of dividers 215, 216 divide signals E_{50A} and E_{50B} , respectively, with signal E_{50} to provide signals E_{51} and E_{52} , respectively, corresponding to the terms θ_2/θ_1 and θ_3/θ_1 , respectively, in equations 25 and 26.

40 The reaction acid flow rate signal E_{14} is multiplied with direct current voltage V_{11} , which corresponds to the conversion factor H in equation 23 for converting the flow rate from barrels per hour to tons per day, by a multiplier 217. Multiplier 217 provides a signal E_{53} corresponding to the acid rate AR_1 associated with sensed acid strength A_1 . A multiplier 220 multiplies signal E_{51} from divider 215 and E_{53} together to provide a signal E_{53A} corresponding to acid rate AR_2 which is associated with acid strength A_2 . Another multiplier 221 multiplies signals E_{52} and E_{53} together to provide a signal E_{53B} corresponding to acid rate AR_3 which is associated with acid strength A_3 . Signal E_{15} corresponding to the bottom products flow rate is multiplied with signal E_{17} , corresponding to the alkylate concentration in line 15 by a multiplier 223. The output from multiplier 223 is multiplied with voltage V_{12} by a multiplier 224 to provide a signal E_{54} corresponding to the alkylate rate ALR . Voltage V_{12} corresponds to the conversion factor J in equation 24.

60 Signal E_{12} from olefin signal means 41 is applied to a ϕ computer 225 along with signal E_{11} and direct current voltages V_8 and V_{13} through V_{20} . Referring now to FIG. 8, voltage V_6 is again subtracted from signal E_{11} to provide a signal corresponding to the term $(A_1 - A_{90})$ in equations 20 and 21 by subtracting means 226. A multiplier 229 effectively squares the signal from subtracting means 226 while another multiplier 230 multiplies the signal from multiplier 229 with voltage V_{13} cor-

responding to the term 0.05582 in equation 20. A multiplier 231 multiplies the output from subtracting means 226 with voltage V_{14} corresponding to the term 0.5115. The output from subtracting means 226 is effectively raised to the fifth power by a logarithmic amplifier 234. The output from amplifier 234 is multiplied with a voltage V_{15} , corresponding to the exponent 5, by a multiplier 235. An antilog circuit 236 which may be an operational amplifier having a function generator, of the type manufactured by Electronics Associates as their part number PC-12, as a feedback network provides a signal corresponding to the term $(A_1 - A_{90})^5$ in equation 20. A multiplier 240 multiplies the output from circuit 236 with voltage V_{16} corresponding to the term 0.00001363 in equation 20. Summing means 241 sums the outputs from multiplier 231, 240 to provide a signal to subtracting means 242. Subtracting means 242 subtracts the output by multiplier 230 from the output provided by summing means 241 to provide a signal E_{56} corresponding to the term ϕ_L .

Similarly, an amplifier 234A, a multiplier 235A, an antilog circuit 236A cooperate to provide a signal corresponding to $(A_1 - A_{90})^3$ using voltage V_{17} corresponding to the exponent 3. Amplifier 243 having unity gain inverts the signal from circuit 236A to provide a signal which is multiplied with a voltage V_{30} , corresponding to the term 0.003609 in equation 21, by a multiplier 244 to provide a signal E_{57} which corresponds to the term ϕ_u .

Voltages V_{18} , V_{19} correspond to the ratios M_L and M_U in equation 22, which for the particular alkylation unit have been selected at 35 percent and 60 percent, respectively. Subtracting means 247, 246 subtract voltage V_{18} from signal E_{12} and signal E_{12} from voltage V_{19} , respectively, to provide outputs corresponding to the term $(M - M_L)$ and $(M_U - M)$, respectively, to dividers 251 and 250, respectively. Voltage V_{18} is subtracted from voltage V_{19} by subtracting means 248 to provide a signal corresponding to $M_U - M_L$ in equation 22. Dividers 250, 251 divide the outputs from subtracting means 246, 247 by the signal from subtracting means 248 to provide outputs to multipliers 252 and 253, respectively. Multiplier 252 multiplies the output from divider 250 with signal E_{56} while multiplier 253 multiplies the output from the divider 251 with signal E_{57} .

Summing means 254 sums the outputs from multipliers 252, 253 to provide a signal E_{58} , corresponding to the term ϕ_{L-U} in equation 22.

Signals E_{56} , E_{57} and E_{58} are applied to electronic switches 257, 257A and 257B, respectively, which are controlled to select one of the signals E_{56} , E_{57} or E_{58} to be used as signal E_{55} . Comparators 258, 259 compare signal E_{12} with voltages V_{19} and V_{18} , respectively. Comparator 258 provides a high level direct current output when signal E_{12} is equal to or more negative than voltage V_{19} and a low level output when signal E_{12} is more positive than voltage V_{19} . Comparator 259 provides a high level direct current output when signal E_{12} is greater than voltage V_{18} and a low level output when signal E_{12} is equal to or less than voltage V_{18} . AND gates 260, 260A and 260B control switches 257, 257A and 257B.

When the M is less than M_L , comparators 258, 259 provide a high level output and a low level output, respectively. Inverters 261, 262 invert the outputs from

comparators 259 and 258, respectively, so that AND gate 260 provides a high level direct current output while AND gates 260A, and 260B provide low level outputs. An electronic switch is rendered conductive by a high level direct current voltage and non-conductive by a low level direct current voltage so that switch 257 is rendered conductive by the output from AND gate 260. When signal E_{12} is less than voltages V_{18} and V_{19} , switch 257 passes signal E_{56} while switches 257A and 257B block signals E_{57} and E_{58} , respectively.

When signal E_{12} is greater than voltages V_{18} and V_{19} , M is greater than M_L and comparators 258, 259 provide a low level output and high level output, respectively. Switch 257A is rendered conductive by the high level output from AND gate 260A receiving high level outputs from comparator 259 and inverter 262, to pass signal E_{57} . AND gates 260, 260B are disabled by low level outputs from comparator 258 and inverter 261, respectively, thereby causing switches 257 and 257B to block signals E_{56} and E_{58} , respectively.

When M is greater than M_L but less than M_U signal E_{12} is greater than voltage V_{18} and less than voltage V_{19} causing comparators 258, 259 to provide high level outputs. AND gate 260B provides a high level output in response to high level outputs from comparators 258, 259 while AND gates 260, 260A provide low level outputs in response to the low outputs from inverters 261 and 262, respectively. Switch 257B passed signal E_{58} in response to the high level output from AND gate 260B, while switches 257, 257A block signals E_{56} and E_{57} , respectively, in response to the low level outputs from AND gate 260 and 260A, respectively.

Similarly, ϕ computers 225A, 225B receive all of the signals and voltages that computer 225 receives with the exception that computers 225A, 225B receive signals E_{11A} and E_{11B} , respectively, in lieu of signal E_{11} to provide signals E_{55A} and E_{55B} corresponding to ϕ_2 and ϕ_3 , respectively, of equations 15, 17 and 16, 18, respectively.

It is necessary to compute the profits for the increased and decreased acid strengths A_2 and A_3 conditions. Referring to FIG. 6, a p_2 computer 265 provides a signal E_{60} corresponding to the term p_2 in equations 15, 17, 29, 30, 32 and 33 in accordance with signals E_{53} , E_{53A} , E_{54} , E_{55} and E_{55A} and voltages V_{21} , V_{22} . Referring to FIG. 9, subtracting means 266 subtracts signal E_{53A} from signal E_{53} to provide an output, which corresponds to the term $(AR_1 - AR_2)$ in equation 17, to a multiplier 267. Multiplier 167 multiplies the output from subtracting means 266 with voltage V_{21} , which corresponds to the term V_A in equation 17. Subtracting means 269 subtracts signal E_{55} from signal E_{55A} to provide a signal corresponding to the term $(\phi_2 - \phi_1)$ in equation 17, to a multiplier 270. A multiplier 271 multiplies voltage V_{22} , which corresponds to the term V_o , and signal E_{54} together to provide an output to multiplier 270. Multiplier 270 multiplies the outputs from subtracting means 269 and multiplier 271 to provide a signal corresponding to the product $(\phi_2 - \phi_1) (ALR) (V_o)$. Summing means 272 sums the outputs from multipliers 267, 270 to provide signal E_{60} .

A computer 265A operates in a similar manner to provide signal E_{60A} , which corresponds to the term p_3 in equations 18, 29, 30, 32, and 33 except that signals E_{53B} , E_{55B} are used in lieu of signals E_{53A} and E_{55A} , respectively.

Referring to FIGS. 6 and 10, an R and S computer 275 solves equations 31, 32 and 33 to provide signals E_{61} , E_{62} corresponding to the terms R and S, respectively, in accordance with signals E_{11} , E_{11A} , E_{11B} , E_{60} and E_{60A} . Signal E_{11} is subtracted from signal E_{11A} by subtracting means 276, to provide a signal corresponding to the term $(A_2 - A_1)$ in equation 33. The signal from subtracting means 276 is multiplied by signal E_{60A} by a multiplier 277 to provide a signal corresponding to the term $p_3(A_2 - A_1)$ in equation 33. Subtracting means 280 subtracts signal E_{11B} from signal E_{11} to provide a signal, corresponding to the term $(A_1 - A_3)$ in equation 33, which is multiplied with signal E_{60} by a multiplier 281 to provide a signal corresponding to $p_2(A_1 - A_3)$. Summing means 282 sums the signals from multipliers 277, 281 to provide a signal corresponding to the numerator of equation 33.

Multipliers 283, 284 and 285 effectively square signals E_{11} , E_{11A} and E_{11B} , respectively, to provide signals corresponding to A_1 , A_2^2 and A_3^2 , respectively. Subtracting means 288 subtracts the output provided by multiplier 284 from the output provided by multiplier 283 to provide a signal corresponding to the term $(A_1^2 - A_2^2)$ in equations 29, 31 and 32. A multiplier 289 multiplies the output from the subtracting means 288 with signal E_{11B} to provide a signal corresponding to $A_3(A_1^2 - A_2^2)$ in equation 31. Subtracting means 290 subtracts the output provided by multiplier 285 from the output provided by multiplier 284 to provide a signal corresponding to the term $(A_2^2 - A_3^2)$ in equations 31, 32. The output from subtracting means 290 is multiplied with signal E_{11} by a multiplier 291 to provide a signal which corresponds to the term $A_1(A_2^2 - A_3^2)$ in equation 31. Subtracting means 294 subtracts the output provided by multiplier 283 from the output provided by multiplier 285 to provide a signal corresponding to the term $(A_3^2 - A_1^2)$ in equations 31, 32. A multiplier 295 multiplies the output from subtracting means 294 with signals E_{11A} to provide a signal corresponding to the term $A_2(A_3^2 - A_1^2)$ in equation 31. The outputs of multipliers 289, 291 and 295 are summed by summing means 296 to provide a signal corresponding to the term D in equations 29 through 33. A divider 297 divides the output from summing means 282 with the output from summing means 296 to provide signal E_{62} .

The output from subtracting means 288, 294 is multiplied with signals E_{60A} and E_{60} respectively, by multipliers 299 and 300, respectively, to provide signals corresponding to the terms $p_3(A_1^2 - A_2^2)$ and $p_2(A_3^2 - A_1^2)$, respectively, in equation 32. The signals from multipliers 299, 300 are summed by summing means 301 to provide a signal corresponding to the numerator in equation 32. The signal from summing means 301 is divided by the signal from summing means 296 by a divider 302 to provide signal E_{61} .

Referring to FIGS. 6 and 11, control means 305 provides signal E_{16} in accordance with signals E_{11} , E_{50} , E_{53} , E_{60} , E_{60A} , E_{61} and E_{62} and voltages $V_6 - V_{10}$, V_{11} , V_{23} and V_{24} . A comparator 302 determines whether equation 4 or 5 will control the acid strength by comparing signal E_{62} to a zero reference, such as ground 301. Equation 4 is used in controlling the alkylation unit when signal E_{62} has a negative value, while equation 5 is used when signal E_{62} is positive or substantially zero. When signal E_{62} is positive or equal to zero, comparator 302 provides a low level direct current signal E_{68} .

Comparator 302 provides a high level output when signal E_{62} is negative. Thus, equation 4 will control when signal E_{68} is at a high level while equation 5 will control when signal E_{68} is at a low level as hereinafter explained.

SECOND ORDER EQUATION CONTROL

10 A multiplier 310, a divider 311 and an inverting amplifier 312, having unit gain, comprise a computer for solving equation 8 for A_0 , the optimum reaction acid strength, and providing a signal E_{63} corresponding thereto. Multiplier 310 multiplies signal E_{62} with voltage V_{23} , corresponding to the term 2S. Divider 311 divides signal E_{61} with the signal from multiplier 310 to provide a signal corresponding to $R/2S$, which is inverted by amplifier 312 to provide signal E_{63} .
 Subtracting means 313 subtracts the acid strength 20 signal E_{11} from signal E_{63} to provide a signal E_{64} . Signal E_{64} corresponds to the required change in the reaction acid strength to achieve the optimum reaction acid strength. However, as stated previously, the change in the reaction acid strength must not exceed the predetermined constraint value Δ . When the required change is greater than Δ , it is necessary that the acid strength be changed in the direction indicated by the required change but by the amount Δ . Since signal E_{64} may be a negative or positive direct current signal, an absolute value signal E_{65} is derived from signal E_{64} by the cooperation of multipliers 235B and 316, a logarithmic amplifier 234B and an anti-log circuit 236B. Multiplier 316 effectively squares signal E_{64} while logarithmic amplifier 234B, multiplier 235, receiving direct current voltage V_{24} corresponding to a value of 0.5 and anti-log circuit 236B obtain the square root of the signal from multiplier 316 to provide signal E_{65} . A comparator 320 determines whether or not the required change to achieve the optimum reaction acid strength is greater than the constraint change Δ . Comparator 320 compares absolute value signal E_{65} with voltage V_{10} , corresponding to constraint change Δ , to provide a direct current signal E_{69} . Signal E_{69} is at a high level when signal E_{65} is greater than voltage V_{10} and at a low level when signal E_{65} is equal to or less than voltage V_{10} .

50 Comparator 320 controls an electronic switch 323 to pass or block signal E_{64} so that signal E_{64} may be used in changing the system acid strength when the required change does not exceed the constraint change Δ . An inverter 321 inverts signal E_{69} so that when signal E_{69} is at a low level, inverter 321 provides a high level output to an electronic switch 323 rendering switch 323 conductive to pass signal E_{64} . If other conditions, as hereinafter described, are met, signal E_{64} will be used to develop signal E_{16} .

55 When the required change to achieve the optimum acid strength is greater than the constraint change Δ , the acid strength is changed by the amount Δ . Inverted signal E_{69} from inverter 321 changes to a low level causing switch 323 to block signal E_{64} so that signal E_{64} cannot affect the acid strength. However, the change to the acid strength by the amount Δ must be in the direction determined by the polarity of signal E_{64} . It is obvious that if the absolute value of signal E_{64} is greater than zero, then signal E_{64} will be some value other than zero.

Comparators 328, 329 compare signal E_{64} with a zero reference, which may be ground 301, to determine the polarity of signal E_{64} . Comparators 328, 329 provide signals to AND gates 330 and 331, respectively. AND gates 330 and 331, OR gates 332 and 333, control electronic switches 336 and 337. Switch 336 receives voltage V_{10} while switch 337 receives an inverted voltage V_{10} , corresponding to $a-\Delta$ from an inverting amplifier 334 receiving voltage V_{10} . AND gates 330, 331 are controlled by signal E_{68} and by comparators 328 and 329, respectively. Thus AND gates 330, 331 are enabled by signal E_{68} which is at a high level, since the control of the alkylation unit by the second order equation is being described. When signal E_{64} is positive, comparators 328, 329 provide a high level signal and a low level signal, respectively. AND gate 330 provides a high level signal to switch 336 in response to high level signals applied to AND gate 330 causing switch 336 to pass voltage V_{10} to an electronic switch 338. Switch 338 allows the acid strength to be changed by the amount Δ when rendered conductive. Switch 338 is rendered conductive when the optimum acid strength is greater than Δ . An AND gate 342 receiving signals E_{68} and E_{69} renders switch 338 conductive when signals E_{68} and E_{69} are at high levels and non-conductive when signal E_{68} or E_{69} is at a low level.

An electronic switch 339 passes the passed signal from switch 323 or 338 when the profit equation is a second order equation so that the alkylation unit is controlled in accordance with equation 4 and blocks the passed signal from switch 323 or 338 when the profit equation is linear so that the alkylation unit is not controlled in accordance with equation 4. Since the second order equation operation is being described, signal E_{68} is at a high level rendering switch 339 conductive to pass a signal from switch 323 or 338.

Summing means 345 sums the passed signal from switch 338 with voltage E_{11} to provide a signal E_{75} corresponding to a new target acid strength. A comparator 346 determines whether the new target acid strength is equal to or greater than A_{90} to prevent undesirable side reactions such as olefin polymerization. Comparator 346 compares signal E_{75} with voltage V_6 , corresponding to A_{90} , to control an electronic switch 347, receiving voltage V_6 and signal E_{75} . When the new target acid strength is less than the minimum allowable acid strength A_{90} , switch 347 is controlled by the output from comparator 346 to pass voltage V_6 and block signal E_{75} . When the new target acid strength is equal to or greater than voltage V_6 , electronic switch 347 is controlled by the output from comparator 346 to pass signal E_{75} from summing means 345 and to block voltage V_6 . The signal or voltage passed by switch 347 determines the acid strength for the alkylation unit.

Signal E_{75} or voltage V_6 , whichever is passed by switch 347, is converted to signal E_{16} corresponding to the discharge acid flow rate by a computer 200C, dividers 350 and 351, and a multiplier 352. Computer 200C operates in a manner similar to the operation of computer 200, heretofore described in detail, except that signal E_{75} or voltage V_6 is used in lieu of signal E_{11} and computer 200C provides a signal E_{76} , which corresponds to the new acid strength A_N , instead of signal E_{50} . Signal E_{76} is divided by signal E_{50} by divider 350 to provide a signal corresponding to θ_N/θ_1 . The signal from

divider 350 is multiplied with signal E_{53} by multiplier 352 to provide a signal corresponding to the new acid rate AR_N . Divider 351 provides signal E_{16} by dividing the AR_N signal with voltage V_{11} .

When signal E_{64} is negative, comparators 328, 329 provide a low level output and a high level output, respectively, to control switches 337 and 336 to block voltage V_{10} and to pass the inverted voltage V_{10} , respectively. When comparator 320 provides a high level output, the inverted voltage V_{10} passes through switch 339 to be used in calculating signal E_{16} , as previously mentioned, to decrease the acid strength, if other conditions which are hereinafter described are met.

15 LINEAR PROFIT EQUATION OPERATION

Comparators 328A, 329A compare signal E_{60A} and E_{60B} , respectively, corresponding to differential profit positions p_2 and p_3 , respectively with a ground, corresponding to differential profit position p_1 . Comparators 328A, 329A cooperate with AND gate 330A, 331A in the same manner as comparators 328, 329 cooperated with AND gates 330 and 331. AND gates 330A and 331A are enabled, when equation 5 is the controlling equation, by a high level output from an inverter 368 inverting signal E_{68} . AND gates 330A, 331A are disabled by a low level output from inverter 368 which occurs when alkylation unit is being controlled in accordance with equation 4 so that comparators 328A, 329A have no effect.

For the condition that differential profit position p_2 is greater than differential profit position p_1 , comparator 328A, 329A provide a high level and a low level output, respectively. Comparator 328A output passes through enabled AND gate 330A to render switch 336 conductive while a low level output provided by AND gate 331A in response to comparator 329A output renders switch 337 non-conductive, respectively. The acid strength will then be increased by the amount Δ as heretofore described. Conversely, when p_3 is greater than zero, comparators 328A and 329A and AND gates 330A, 331A render switches 336 and 337, respectively, non-conductive and conductive, respectively, so that the acid strength is decreased by the amount Δ .

Since switch 338 is rendered non-conductive by the low level of signal E_{68} , the signal passed by switch 336 or 337 is now passed by another electronic switch 369 which is rendered conductive by a high level output from comparator 328A or 329A passing through an AND gate 330A or 331A and an OR gate 370 to summing means 345.

When position p_1 is greater than position p_2 and p_3 , comparators 328A, 329A provide low level outputs rendering switch 369 non-conductive. Since switches 339 and 369 are rendered non-conductive, the acid strength will not be changed.

The system of the present invention, as heretofore described, controls an alkylation unit so that the reaction acid in the alkylation unit is at an optimum strength. The reaction acid strength is controlled as a function of the economic values of acid being fed to the alkylation unit and the octane rating of the alkylate produced by the alkylation unit. The control system varies the reaction acid strength under a restrictive condition that the reaction acid strength may not be less than the predetermined level.

What is claimed is:

1. A system for controlling the strength of a reaction acid in an alkylation unit wherein an isoparaffin is reacted with an olefin in the presence of the reaction acid to provide an acid-hydrocarbon mixture to a settler where a hydrocarbon product is separated from the reaction acid and provided to a debutanizer tower whose bottom products include alkylate and a portion of the reaction acid is recycled while the remaining reaction acid is discharged from the alkylation unit and wherein fresh acid is added to the recycled acid to affect the strength of the reaction acid, comprising means for controlling the strength of the reaction acid in accordance with a control signal, means for sensing the flow rates of one of the acid and the bottom products and providing signal representative thereof, means for sensing concentrations of different constituents of the olefin and providing corresponding signals, means for sensing the concentration of the alkylate in the bottom products and providing a signal corresponding thereto, means for sensing the strength A_1 of the reaction acid and providing a signal corresponding thereto, means for providing signals corresponding to the economic values V_A and V_o of acid and of octane of the alkylate, respectively, and means connected to the sensing means, to the control means and to the value signal means for providing the control signal to the control means in accordance with the signals from the sensing means and the value signal means to achieve an optimum reaction acid strength.

2. A system as described in claim 1 in which the control signal means includes means for providing signals corresponding to an acid strength A_2 greater than the sensed acid strength A_1 , to an acid strength A_3 less than the sensed acid strength A_1 , and to a reference acid strength A_{90} ; means connected to the flow rate sensing means, olefin sensing means, to the acid strength sensing means and to the economic value sensing means for providing signals corresponding to anticipated changes p_2 and p_3 in profit associated with the acid strengths A_2 and A_3 , respectively, in accordance with the acid strength A_1 , A_2 , A_3 and A_{90} signals, the acid flow rate signal, the bottoms product flow rate signal, and the economic value signals, and a network connected to the profit change signal means, to the acid strength sensing means, to the control means and to the acid strength signal means for providing a signal, corresponding to a desired acid strength, to the control means as the control signal in accordance with the acid strength A_1 , A_2 and A_3 signals and the profit change p_2 and p_3 signals.

3. A system as described in claim 2 in which the profit change signal means includes means connected to the economic value signal means and receiving signals corresponding to octane adder factors ϕ_1 , ϕ_2 and ϕ_3 , to acid rates AR_1 , AR_2 and AR_3 and to an alkylate rate ALR for providing the p_2 and p_3 signals in accordance with the economic value signals, the received signals and the following equations:

$$p_2 = (\phi_2 - \phi_1)(ALR)(V_o) - (AR_1 - AR_2)(V_A) \text{ and}$$

$$p_3 = (\phi_3 - \phi_1)(ALR)(V_o) - (AR_1 - AR_2)(V_A),$$

where ϕ_1 , ϕ_2 and ϕ_3 are the octane adder factors associated with the sensed acid strength A_1 and the predetermined acid strengths A_2 and A_3 , respectively, and where AR_1 , AR_2 and AR_3 are the acid rates associated with the sensed acid strength A_1 and the

predetermined acid strength A_2 and A_3 , respectively; rate signal means connected to the flow rate sensing means, to the acid strength sensing means, to the alkylate sensing means, to the acid strength signal means, and to the $p_2 - p_3$ signal means for providing the ALR , AR_1 , AR_2 and AR_3 rate signals to the $p_2 - p_3$ signal means in accordance with the signals from the flow rate sensing means and the acid strength A_1 , A_2 , A_3 and A_{90} signals; and octane adder factor means connected to the acid strength sensing means, to the acid strength signal means, to the olefin sensing means and to the circuit and receiving direct current voltages corresponding to constants K_f , K_g and K_h for providing the octane adder factors ϕ_1 , ϕ_2 and ϕ_3 signals to the circuit in accordance with the sensed acid strength A_1 signal, the olefin constituents signals, the reference acid strength A_{90} signal and the received voltages.

4. A system as described in claim 3 in which the rate signal means includes means connected to the flow rate sensing means, to the circuit and receiving direct current voltages corresponding to conversion constants H and J for providing the AR_1 and the ALR signals in accordance with the sensed acid flow rate FR_A , the sensed bottom products flow rate FR_p , the alkylate concentration ALK signal, the received voltage and the following equations:

$$AR_1 = (H)(FR_A) \text{ and}$$

$$ALR = (J)(FR_{BP})(ALK),$$

30 acid consumption factor signal means connected to the acid strength sensing means and to the acid strength signal means and receiving the voltages corresponding to the constants K_f , K_g , K_h , K_i and K_j for providing acid consumption factor θ_1 , θ_2 and θ_3 signals in accordance with the sensed acid strength A_1 signal, the reference acid strength signal A_{90} , the received voltages and the following equations:

$$\theta_1 = K_f + K_g(A_1 - A_{90}) + K_h(A_1 - A_{90})^2 + K_i(A_1 - A_{90}) + K_j(A_1 - A_{90})^4 + K_k(A_1 - A_{90})^5$$

$$\theta_2 = K_f + K_g(A_2 - A_{90}) + K_h(A_2 - A_{90})^2 + K_i(A_2 - A_{90})^3 + K_j(A_2 - A_{90})^4 + K_k(A_2 - A_{90})^5$$

$$\theta_3 = K_f + K_g(A_3 - A_{90}) + K_h(A_3 - A_{90})^2 + K_i(A_3 - A_{90})^3 + K_j(A_3 - A_{90})^4 + K_k(A_3 - A_{90})^5$$

45 where θ_1 , θ_2 and θ_3 are acid consumption factors associated with the sensed acid strength A_1 and the predetermined acid strengths A_2 and A_3 , respectively, and means connected to the AR_1 signal means, to the θ_1 , θ_2 and θ_3 signal means and to the $p_2 - p_3$ signal means 50 for providing the AR_2 and AR_3 signals to the $p_2 - p_3$ signal means in accordance with the AR_1 , θ_1 , θ_2 and θ_3 signals and the following equations:

$$AR_2 = (\theta_2 / \theta_1) AR_1, \text{ and}$$

$$AR_3 = (\theta_3 / \theta_1) AR_1.$$

55 5. A system as described in claim 4 in which the ϕ_1 , ϕ_2 and ϕ_3 signal means includes means connected to the olefin sensing means and receiving a direct current voltage corresponding to the term 100 for providing a ratio M signal in accordance with the olefin constituents signals, the received voltage and the following equation:

$$M = (\text{Propylene/Olefins}) \times 100$$

65 where propylene and olefins refer to their concentrations in the reactions, and a plurality of networks, each network connected to the ratio M signal means, to the acid strength signal means and receiving direct current

voltages corresponding to reference ratios M_U and M_L and constants K_a through K_d , one of the networks being connected to the acid strength sensing uses the received voltages and signals to provide an octane factor ϕ_1 , ϕ_2 or ϕ_3 signal associated with the acid strength A_1 , A_2 or A_3 signal in accordance with the following equation:

$$\phi_L = K_a(A - A_{90}) + K_b(A - A_{90})^2 + K_c(A - A_{90})^5,$$

where the term A without a subscript refers to the associated acid strength A_1 , A_2 or A_3 , ϕ_L corresponds to an octane adder factor ϕ_1 , ϕ_2 or ϕ_3 when the ratio M signal is equal to or less than the reference ratio M_L voltage, in accordance with the following equation:

$$\phi_U = +K_d(A - A_{90})^3$$

where ϕ_U corresponds to an octane adder factor ϕ_1 , ϕ_2 or ϕ_3 when the ratio M signal is equal to or greater than the reference ratio M_U voltage, and in accordance with the next two previous equations and the following equation:

$$\phi_{L-U} = \phi_L(M_U - M/M_U - M_L) + \phi_U(M - M_L/M_U - M_L)$$

where ϕ_{L-U} corresponds to an octane adder factor ϕ_1 , ϕ_2 or ϕ_3 when the ratio M signal is greater than the reference ratio M_L voltage but less than the reference ratio M_U voltage.

6. A system as described in claim 5 in which the general profit P equation for the alkylation unit may be a second order equation as follows:

$$p = Q + RA + SA^2, \quad \text{or}$$

a linear equation as follows:

$$p = Q + RA$$

where Q , R and S are constants and A is an acid strength, and the control signal network includes means connected to the circuit, to the acid strength signal means and to the acid strength sensing means for providing signals corresponding to R and S in accordance with the acid strength A_1 , A_2 and A_3 signals, and means connected to the R and S signal means for determining whether the profit equation is a second order equation or a linear equation and providing a signal corresponding to an optimum acid strength A_0 when the profit equation is a second order equation and providing a signal corresponding to a predetermined change Δ in acid strength when the profit equation is a linear equation and the sensed acid strength A_1 is not an optimum acid strength.

7. A system as described in claim 6 in which the control means further comprises means connected to the acid strength signal means, to the control means and to the network providing the control signal for permitting the control signal to be provided to the control means when the desired acid strength is equal to or greater than the reference acid strength A_{90} and not providing the control signal to the control means when the desired acid strength is less than the reference acid strength A_{90} .

8. A system as described in claim 6 in which the R and S signal means provide the R and S signals in accordance with the following equations:

$$R = [p_2(A_3^2 - A_1^2) + p_3(A_1^2 - A_2^2)]/D,$$

$$S = [p_2(A_1 - A_3) + p_3(A_2 - A_1)], \text{ and}$$

$$D = A_1(A_2^2 - A_3^2) + A_2(A_3^2 - A_1^2) + A_3(A_1^2 - A_2^2).$$

9. A system as described in claim 6 in which the determining means includes means connected to the R and S signal means for providing the optimum acid

strength A_0 signal in accordance with the R and S signals and the following equation:

$$A_0 = -R/2S,$$

change signal means connected to the A_0 signal means and to the acid strength sensing means for providing a change signal corresponding in magnitude to the difference between the A_0 and A_1 signals and in polarity to a relationship between the A_0 and A_1 signals, first switching means connected to the change signal means and receiving direct current voltages of opposite polarities, one received voltage corresponds to the predetermined change Δ in one direction while the other voltage corresponds to the predetermined change Δ in an opposite direction, for providing the one received voltage when the change signal from the change signal means is of one polarity and the other received voltage when the change signal is not of the one polarity, second switching means connected to the first switching means and to the change signal means for passing the change signal while blocking a predetermined change voltage from the first switching means when the change signal has a smaller, or equal, amplitude than a predetermined change voltage, and blocking the change signal from the change signal means while passing a predetermined change voltage from the first switching means when the change signal has a larger amplitude than a predetermined change voltage.

10. A method for controlling the strength of a reaction acid in an alkylation unit wherein an isoparaffin is reacted with an olefin in the presence of the reaction acid to provide an acid-hydrocarbon mixture to a settler where a hydrocarbon product is separated from the reaction acid and provided to a debutanizer tower whose bottom products include alkylate and a portion of the reaction acid is recycled while the remaining reaction acid is discharged from the alkylation unit and wherein fresh acid is added to the recycle acid to affect the strength of the reaction acid, which comprises the following steps:

controlling the strength of the reaction acid in accordance with a control signal, sensing the flow rates of the reaction acid and the bottom products, providing signals corresponding to the sensed flow rates, sensing the concentrations of different constituents of the olefin, providing signals corresponding to the sensed concentrations of constituents of the olefin, sensing the concentration of alkylate in the bottom products, providing a signal corresponding to the sensed alkylate concentration, sensing the strength A_1 of the reaction acid, providing a signal corresponding to the sensed acid strength, providing signals corresponding to the economic values V_A and V_O of the acid and of octane rating of the alkylate, respectively, and providing the control signal in accordance with the signals corresponding to the sensed flow rate, the sensed acid strength, the sensed constituent concentrations and the economic value signals.

11. A method as described in claim 10 in which the providing of the control signal step includes the steps of providing signals corresponding to an acid strength A_2 greater than the sensed acid strength A_1 , to an acid strength A_3 less than the sensed acid strength A_1 and to a reference acid strength A_{90} ; providing signals cor-

responding to anticipated changes p_2 and p_3 in profit associated with the acid strengths A_2 and A_3 , respectively, in accordance with the acid strength A_1 , A_2 , A_3 and A_{90} signals, the acid flow rate signal, the bottom product flow rate signal, and the economic value signals; and providing a signal corresponding to a desired acid strength as the control signal in accordance with the acid strength A_1 , A_2 and A_3 signals and the profit change p_2 and p_3 signals.

12. A method as described in claim 11 in which the providing of the profit change signal steps includes the steps of providing signals corresponding to octane adder factors θ_1 , θ_2 and θ_3 in accordance with the sensed acid strength A_1 signal, the reference acid strength A_{90} signal, the olefin constituents signals; providing rate signals ALR , AR_1 , AR_2 and AR_3 corresponding to an alkylate rate, an acid rate associated with acid strength A_1 , an acid rate associated with acid strength A_2 and an acid rate associated with acid strength A_3 , respectively, in accordance with the flow rate signals, the alkylate concentration signal and the acid strength A_1 , A_2 , A_3 and A_{90} signals, and providing the p_2 and p_3 signals in accordance with the economic value signals, the octane adder factors ϕ_1 , ϕ_2 and ϕ_3 signals, the ALR signal and the AR_1 , AR_2 and AR_3 signals in the following equations:

$$p_2 = (\phi_2 - \phi_1)(ALR)(V_0) - (AR_1 - AR_2)(V_A) \text{ and}$$

$$p_3 = (\phi_3 - \phi_1)(ALR)(V_0) - (AR_1 - AR_2)(V_A).$$

13. A method as described in claim 12 in which the step of providing rate signals includes providing the AR_1 rate signal and the ALR rate signal in accordance with the signal corresponding to the flow rate FR_A of the acid and the signal corresponding to the flow rate FR_{BP} of the sensed bottom product and the signal corresponding to the alkylate ALK concentration and the following equations:

$$AR_1 = (H)(FR_A) \text{ and}$$

$$ALR = (J)(FR_{BP})(ALK)$$

where H and J are conversion factors, providing acid consumption factor θ_1 , θ_2 and θ_3 signals associated with the acid strength A_1 , A_2 and A_3 in accordance with the sensed acid strength A_1 signal, the reference acid strength A_{90} signal and the acid strength signals A_2 and

A_3 and the following equations:

$$\theta_1 = K_f + K_g(A_1 - A_{90}) + K_h(A_1 - A_{90})^2 + K_i(A_1 - A_{90})^3 + K_j(A_1 - A_{90})^4 + K_k(A_1 - A_{90})^5$$

$$\theta_2 = K_f + K_g(A_2 - A_{90}) + K_h(A_2 - A_{90})^2 + K_i(A_2 - A_{90})^3 + K_j(A_2 - A_{90})^4 + K_k(A_2 - A_{90})^5$$

$$\theta_3 = * K_f + K_g(A_3 - A_{90}) + K_h(A_3 - A_{90})^2 + K_i(A_3 - A_{90})^3 + K_j(A_3 - A_{90})^4 + K_k(A_3 - A_{90})^5$$

where K_f , K_g , K_h , K_i , K_k and K_j are constants, and providing the AR_2 and AR_3 rate signals in accordance

10 with the AR_1 rate signals and the acid consumption factor θ_1 , θ_2 and θ_3 signals and the following equations:

$$AR_2 = (\theta_2/\theta_1) AR_1, \text{ and } AR_3 = (\theta_3/\theta_1) AR_1$$

15 14. A method as described in claim 12 in which the step of providing the θ_1 , θ_2 and θ_3 signals include providing a ratio M signal in accordance with the olefin constituent signals and the following equation:

$$M = (\text{Propylene/Olefins}) \times 100$$

20 where propylene and olefins refer to their concentrations, and in which each θ_1 , θ_2 or θ_3 signal is provided in accordance with the associated acid strength A_1 , A_2 or A_3 signal and the reference acid strength signal A_{90} and the following equation:

$$25 \theta_L = K_a(A - A_{90}) + K_b(A - A_{90})^2 + K_c(A - A_{90})^5,$$

where the term A without a subscript refers to the acid strength A_1 , A_2 or A_3 signal other than the reference acid strength when the ratio M signal is equal to or less than a reference ratio M_L signal, in accordance with the following equation:

$$\theta_U = +K_d(A - A_{90})^3$$

where the ratio M signal is equal to or greater than the reference ratio M_U signal, and in accordance with the following equation:

$$\theta_{L-U} = \theta_L(M_U - M/M_U - M_L) + \theta_u(M - M_L/M_U - M_L)$$

40 where θ_{L-U} corresponds to an octane adder factor ϕ_1 , ϕ_2 or ϕ_3 when the ratio M signal is greater than the reference ratio M_L voltage but less than the reference ratio M_U voltage.
